SIPHON GENERATOR AND CIRCULATOR FOR LOCOMOTIVE BOILERS

Application filed December 4, 1930. Serial No. 500,122.

This invention relates to a siphon generator and water circulator for locomotive boilers, designed for use in the fire-boxes of such boilers for increasing the steam generating capacity of the boiler and promoting the circulation of the water between the various water containing parts of the boiler. More particularly the invention relates to a siphon generator and water circulator which will increase the steam generating area of the boiler to a material extent, while at the same time establishing a flow of water between the side water legs and the water space above the crown sheet, so as to effect a siphonic flow of the water over the crown sheet to prevent any portion thereof from being damaged by heat when the water level is low and to promote a circulation of the water in the side water legs where the circulation is normally sluggish, so as to prevent the precipitation of mud and other solids on the mud ring and liability of mud burning and cracking of the fire-box sheets.

As is well known, a locomotive siphon is a device applied to the fire-box and sometimes to the combustion chamber of a locomotive boiler for the purpose of increasing the heating surface and at the same time acting as a protection to the crown sheet, the rapid circulation set up by the siphon causing an overflow of water onto the crown sheet, thus preventing the crown sheet from becoming overheated when the water is low and pulling away from the staybolts. Ordinarily the locomotive boiler crown sheet is positioned on an inclined plane, the highest point being at the forward end near the back flue sheet. Therefore, if the water level in the boiler falls below the proper height, the front part of the fire-box or crown sheet will become uncovered and, being subjected to the radiant heat in the fire-box, becomes overheated and the sheets are pulled away from the staybolts because of the internal pressure exerted. This dropping of the locomotive crown sheet sets up a very dangerous condition as a result of which a violent explosion may follow, with possible loss of life, due to the sudden flashing into steam of large quantities of hot water under high pressure.

A type of locomotive siphon of the character referred to in common use is one comprising one or more transversely flat, substantially triangular drop boxes or water chambers arranged within the fire-box and having a longitudinally extending top outlet slot communicating with the water space above the crown sheet, the walls of said outlet slot being defined by flanged walls of the water box which are fitted and welded in a similarly shaped opening cut in the crown sheet, the box having an inlet neck at the base of its front portion which is welded to the throat sheet and communicates with a lower part of the water containing space of the boiler formed by the front water leg. An objection to this type of siphon is that its inlet neck is of restricted cross-sectional area compared with the cross-sectional area of the body of the siphon, and as the upper rear portion of the siphon body and the inlet neck are welded or otherwise attached to the crown sheet and throat sheet, respectively, the connections being rigid in order to make them sufficiently strong to withstand the internal steam pressure, such portions of the fire-box sheets and the siphon body and neck are prevented from having proper degrees of expansion and contraction under the internal heat and pressure and are subjected in service to such strains as to cause within a comparatively short period of time cracks or fissures in the attached parts of the siphon which set up a dangerous condition in the fire-box. Accordingly frequent examinations and expensive repairs are required in order to keep the siphon in a safe working condition. Attempts have been made to overcome such objections to siphons constructed and attached in the manner described, by connecting siphon inlet tubes with the side water legs in order to secure greater flexibility of the connections, but these prior efforts for one reason or another have been without material success so far as we are aware.

In another application for patent filed of even date herewith, Serial No. 500,121, we have shown the application of our invention to a locomotive fire-box boiler of stand-

ard type without a combustion chamber, and as broadly described and claimed there-in our novel construction of siphon steam generator and water circulator comprising 5 a longitudinally extending trough supported solely by the crown sheet within the fire-box and opening at its top through the crown sheet into the water space there-above, said trough being of substantially 10 equal depth throughout and connected at its base by flexible tubes with a side sheet of the fire-box and the related side water leg, whereby the steam generating and water circu-lating capacities of the boiler are in- 15 creased, the deposit of mud and other sedi-mentary matter reduced, and the steam gen-erator and water circulator so arranged as to permit free expansion and contraction of the boiler sheets and parts of the generator 20 and circulator to prevent the formation of cracks and to otherwise overcome the objections referred to as existing in prior devices of this character.

The present application shows a further 25 carrying forward of the invention in its ap-lication to a fire-box boiler having a com-bustion chamber into which the forward ends of the water troughs extend, and sup-plemental tubes connecting said troughs 30 with an inner sheet of the barrel, whereby the steam generating and water circu-lating capacities of the boiler are still further increased.

The object of the present invention, there- 35 fore, is to provide a mode of mounting our improved siphon steam generator and water circulator in a locomotive boiler fire-box having a combustion chamber in such man-ner as to increase the generation of steam 40 and circulation of water in a simple, reliable and efficient manner.

With these and other objects in view, the 45 invention consists of the features of con-struction, combination and arrangement of parts, hereinafter fully described and claimed, reference being had to the accom-panying drawings, in which:—

Fig. 1 is a vertical longitudinal section 50 through the fire-box of a locomotive boiler embodying our invention, taken on line 1—1 of Fig. 2.

Fig. 2 is a vertical transverse section 55 through the fire-box taken on line 2—2 of Fig. 1.

Fig. 3 is a vertical longitudinal section 60 on line 3—3 of Fig. 2.

Fig. 4 is a view similar to Figure 2 through 65 the combustion chamber of the boiler.

Referring now more particularly to the 70 drawings, 1 designates a locomotive fire-box of a standard type comprising a door sheet 2, flue sheet 3, side sheets 4 and a crown sheet 5. The crown sheet is transversely arched or curved as usual and merges into 75 the side sheets, and forming a continuation

of the flue sheet is the inside throat sheet 6. The side sheets and crown sheet extend between and are connected at their ends to the door sheet 2 and flue and throat sheets 3 and 6, respectively, and the crown sheet 70 extends in an inclined plane in an upward and forward direction, its highest point be-ing at its forward end where it connects with the flue sheet. The wrapper of the boiler includes a roof sheet 7, a back head 8, outer 75 fire-box sheets 9, and an outer throat sheet 10. The described parts of the fire-box and wrapper are arranged in the manner well known to provide the front water leg 11, rear water leg 12, side water legs 13, and 80 the water space 14 between the crown sheet 5 and the roof sheet 7. The dotted line 15 represents the normal grate surface. The fire-box is secured to and supported from the outer wrapper or shell by means of the 85 usual longitudinal and transverse rows of staybolts, not shown in detail as unessential to a proper disclosure of our invention. The fire-box is one of that type in which the flue sheet 3 is disposed in advance of the 90 throat sheet 6 and forms with the crown and side sheets a combustion chamber 1* extending forwardly a distance into the barrel 1*. The construction so far described is typical 95 of a type of locomotive boiler in general use and need not for that reason be described in greater detail.

Disposed within the fire-box is one or more siphon generators and water circula-tors embodying our invention, two of such 100 generators and circulators being shown in the present instance, arranged on opposite sides of the longitudinal center of the fire-box and between the same and the fire-box side walls. Each of these siphon generators 105 and water circulators comprises a trough-like body or box 16, which is closed at its bottom and each end and open at its top. This trough-like body may be of the same depth throughout, from end to end thereof, 110 and extends the major portion of the dis-tance between the flue and door sheets, its forward end projecting forwardly beyond the plane of the throat sheet 6 and extend-ing into the combustion chamber 1*. The 115 trough is supported from the crown sheet 5 and communicates at its top with the water space 14. In practice, the trough is prefer-ably fitted and secured in position by cutting away a portion of the crown sheet to form a 120 receiving slot and flanging out the side and end walls of the trough at their upper edges, as shown at 17 and welding such flanged out edges to the edge walls of the slot in the crown sheet, as indicated at 18. An elon-gated passage 19 for the flow of water be-tween the trough and water space 14 is thus 125 provided, whereby, in the operation of the boiler, a constant siphonic flow of the water from the trough into the space 14 and over 130

the crown sheet 5 is secured, so that in the event of the water falling below a normal working level in the boiler, and exposing a portion of the crown sheet, such portion will be protected by the siphonic flow from the trough and overheating of the crown sheet by the heat from the fire-box effectually prevented.

The trough 16 is subjected directly to the radiant heat from the fire-box and acts as a steam generator as well as a siphonic circulator whereby the steam generating area and capacity of the boiler are materially increased. In practice the trough may be of any suitable cross-sectional shape, but it is preferred to make it of greatest width at its base and tapering therefrom gradually and uniformly, and thus diminishing in width, toward the passage 19. The sides of the trough thus converge from the trough bottom toward the flanged side edges 17, whereby the tendency of the upflowing water to be separated by the generated steam bubbles from the side walls of the trough is prevented and the water caused to flow in contact with such walls, thus preventing the same from being left bare and possibly overheated and damaged. These walls of the trough are united by staybolts 20 whereby they are strengthened and reinforced to withstand the imposed strains.

It will be observed that this construction of the drop water trough reduces the size of the opening or openings necessary to be cut in the crown sheet, for the reception of the trough or troughs employed, so that the crown sheet is not deprived of any great portion of its material and remains almost entirely intact and of unitary construction, so that the strength of the crown sheet is not impaired, and all the advantages of a unitary sheet formation remains, including the unbroken integral surfaces over which the water may freely flow. The disadvantages of a non-unitary or built-up type of crown sheet are thereby effectually avoided.

Each trough 16 is connected at regular intervals throughout its length by water circulating tubes 21 with the water leg 13 at the contiguous side of the boiler. Thus the two water troughs 16 communicate through separate groups of tubes 21 with the water legs 13 at the opposite sides of the boiler. The tubes of each set communicate at their upper ends with the bottom of the trough 16 and at their lower ends with the water leg 13 at a desired low level above the level of the mud ring 22. Preferably the ends of the tubes are fitted and rolled or beaded into openings in the bottom of the trough 16 and side sheet 4 and welded to the trough bottom and side sheet. By arranging these tubes so that they connect with the side water leg at a comparatively low level, the

tubes may be bent so as to extend on a longitudinal curve of comparatively wide radius, thus adapting the tubes to bend or flex easily and freely and to permit independent flexing motions of the crown and side sheets and walls of the troughs, without resistance from any of the parts of the fire-box installation, thus overcoming the objections to prior siphons of the character described and any tendency of the fire-box walls, water troughs, or the connections between them to warp or crack.

We also provide supplemental tubes 21^a connecting the bottom of the forwardly extending end of each trough within the combustion chamber 1^a with an inside sheet of the barrel 1^b and the bottom portion of the water space 1^c of the barrel in advance of the throat sheet and the front water leg 11. These tubes 21^a, like the tubes 21, are longitudinally curved to secure flexibility and may have their lower end portions bent to lie in different vertical planes or at different angles to the vertical so as to connect with laterally spaced portions of the water space 1^c. Thus it will be seen that each siphon body or trough 16 is supported directly and wholly from the crown sheet, and is connected by circulating tubes 21 and 21^a of relatively small cross-sectional area, and relatively long in proportion to their sectional area, with the side sheets of the side water legs of the fire-box portion and side water spaces of the barrel portion of the boiler, which tubes are accordingly of freely bendable or flexible character, so that no rigid connections are employed or resistance set up which will prevent the fire-box sheets and the parts of the siphon from adjusting themselves freely and easily to the normal strains.

The form, construction and arrangement of the troughs 16 and tubes 21 and 21^a are further such as to permit of the application to the roof sheet 7 and outer fire-box sheet 9 and companion sheets of the barrel of washout plugs 23 arranged in alignment with the ends of each tube of a group of tubes 21 and 21^a, whereby a washout tool may be readily and conveniently introduced for the purpose of washing the troughs and tubes free from mud and other deposits at desirable intervals. This is of great importance and advantage as the connection of the troughs 16 through the tubes 21 and 21^a with the lower portions of the side water legs of the fire-box and side water spaces of the barrel creates a strong circulation of the water between the crown water spaces and also portions of the side water spaces, tending to keep the latter-named water spaces substantially free from mud and other deposits liable to cause clogging and mud burning and other damages. By this means also the water containing spaces throughout are kept to a still further degree free from

sedimentary deposits and the steam generating capacity and efficiency of the boiler still further increased. Our improved construction of siphon steam generator and water circulator permits of the use of the conventional arch tubes 24 and arch brick 25 without change from conventional practice.

It will be obvious from the foregoing that our improved construction of siphon steam generator and water circulator not only increases the steam generating capacity of a boiler to a greater degree than is possible with ordinary locomotive siphons, but ensures the keeping of the water at a higher degree of purity, and reduces liability of damage due to cracks from internal strains and the expense necessary to keep the boiler in prime working condition. With the use of two siphons and sets of circulating tubes in a fire-box of ordinary type without a combustion chamber, and having 228 square feet of heating surface, the heating surface is increased by the siphons and tubes to an extent of 77 square feet, without interfering with the free combustion of the fuel or circulation of the fuel gases on normal action of the fire-box. In the type of boiler herein disclosed, having a combustion chamber in which the forward ends of the troughs may be extended, thus increasing the length of the troughs, and the use of the tubes 21^a connected therewith, the heating surface of the siphon attachment will be increased from 77 square feet to 103 square feet, with corresponding advantages.

Having thus fully described our invention, we claim:—

1. The combination with a locomotive boiler having a fire-box, a combustion chamber at the front thereof, a side water leg, and a barrel, of a water steaming and circulating device comprising a trough supported by the crown sheet of the fire-box and extending longitudinally of the fire-box and into the combustion chamber, said trough communicating at its top through the crown sheet with the water space of the boiler above the level of the crown sheet, a set of water circulating tubes connecting the trough with the side water leg, and water tubes connecting the part of the trough in the combustion chamber with the water space of the barrel.

2. The combination with a locomotive boiler having a fire-box, a combustion chamber at the front thereof, a side water leg, and a barrel, of a water steaming and circulating device comprising a trough supported by the crown sheet of the fire-box and extending longitudinally of the fire-box and into the combustion chamber, said trough communicating at its top through the crown sheet with the water space of the boiler above the level of the crown sheet, a set

of water circulating tubes connecting the trough with the side water leg, and water tubes connecting the part of the trough in the combustion chamber with the water space of the barrel, all of said tubes being longitudinally curved so as to bend freely and permit ready flexion of the parts of the boiler structure to which said trough and tubes are attached.

3. The combination with a locomotive boiler having a fire-box, a combustion chamber at the front thereof, a side water leg, and a barrel, of a water steaming and circulating device comprising a trough supported by the crown sheet of the fire-box and extending longitudinally of the fire-box and into the combustion chamber, said trough communicating at its top through the crown sheet with the water space of the boiler above the level of the crown sheet, a set of water circulating tubes connecting the trough with the side water leg, water tubes connecting the part of the trough in the combustion chamber with the water space of the barrel, all of said tubes being longitudinally curved to bend freely and permit ready flexion of the parts of the boiler structure to which the trough and tubes are attached, and suitably closed openings in the boiler shell in line with the upper and lower ends of the tubes through which a washout device may be inserted to wash out the trough and tubes.

4. The combination with a locomotive boiler having a fire-box, a combustion chamber at the front thereof, a side water leg, and a barrel, of water steaming and circulating devices arranged at each side of the longitudinal center of the fire-box and each comprising a trough supported by the crown sheet of the fire-box and extending therefrom into the combustion chamber, said trough communicating at its top through the crown sheet with the water space of the boiler above the level of the crown sheet, a set of water tubes connecting each trough with the side water leg at the same side of the fire-box, and water tubes connecting that part of each trough disposed in the combustion chamber with the water space of the barrel.

5. The combination with a locomotive boiler having a fire-box, a combustion chamber at the front thereof, a side water leg, and a barrel, of water steaming and circulating devices arranged at each side of the longitudinal center of the fire-box and each comprising a trough supported by the crown sheet of the fire-box and extending therefrom into the combustion chamber, said trough communicating at its top through the crown sheet with the water space of the boiler above the level of the crown sheet, a set of water tubes connecting each trough with the side water leg at the same side of

the fire-box, and water tubes connecting that part of each trough disposed in the combustion chamber with the water space of the barrel, all of said tubes being longitudinally curved so as to bend freely and permit ready flexion of the parts of the boiler structure to which said trough and tubes are attached.

6. The combination with a locomotive boiler having a fire-box, a combustion chamber at the front thereof, a side water leg, and a barrel, of water steaming and circulating devices arranged at each side of the longitudinal center of the fire-box and each comprising a trough supported by the crown sheet of the fire-box and extending therefrom into the combustion chamber, said trough communicating at its top through the crown sheet with the water space of the boiler above the level of the crown sheet, a set of water tubes connecting each trough with the side water leg at the same side of the fire-box, water tubes connecting that part of each trough disposed in the combustion chamber with the water space of the barrel, all of said tubes being longitudinally curved to bend freely and permit ready flexion of the parts of the boiler structure to which the troughs and tubes are attached, and suitably closed openings in the boiler shell in line with the upper and lower ends of the tubes through which a washout device may be inserted to wash out the troughs and tubes.

In testimony whereof we affix our signatures.
